(57) CLAIM

The ornamental design for a holder for markers and eraser, as shown and described.

DESCRIPTION

FIG. 1 is a perspective view of a holder for markers and eraser showing my new design;

FIG. 2 is a front elevational view thereof;

FIG. 3 is a right side elevational view, the left side being a mirror image thereof;

FIG. 4 is a rear elevational view thereof;

FIG. 5 is top plan view thereof; and,

FIG. 6 is a bottom plan view thereof.

The broken line showing in FIGS. 1, and 3-5, is for illustrative purposes only and forms no part of the claimed design.
